(57) **CLAIM**

The ornamental design for an adjuster, as shown and described.

DESCRIPTION

FIG. 1 is a front view of an adjuster showing a first embodiment of our new design;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a top, right perspective view thereof;

FIG. 8 is a bottom, left perspective view thereof;

FIG. 9 is a front view of an adjuster showing a second embodiment of our new design;

FIG. 10 is a rear view thereof;

FIG. 11 is a top plan view thereof;

FIG. 12 is a bottom plan view thereof;

FIG. 13 is a right side view thereof;

FIG. 14 is a left side view thereof;

FIG. 15 is a top, right perspective view thereof; and,

FIG. 16 is a bottom, left perspective view thereof.

The broken lines shown in FIGS. 4, and 12 illustrate portions of the adjuster that form no part of the claimed design.

1 Claim, 8 Drawing Sheets
